UNITED STATES PATENT OFFICE

95,541

DESIGN FOR A BOAT

Frank J. Piccola, Lynn, Mass.

Application January 11, 1935, Serial No. 54,820

Term of patent 7 years

To all whom it may concern:

Be it known that I, Frank J. Piccola, a citizen of the United States, residing at Lynn, in the county of Essex and State of Massachusetts, have invented a new, original, and ornamental Design for a Boat, of which the following is a specification, reference being had to the accompanying drawings, forming part thereof.

I claim:

The ornamental design for a boat as shown.

FRANK J. PICCOLA.
